United States Patent Office

Des. 183,097
Patented June 24, 1958

183,097

DERRICK

James Howard Holan, Rocky River, Ohio, assignor to J. H. Holan Corporation, Cleveland, Ohio, a corporation of Ohio

Application August 15, 1956, Serial No. 42,609

Term of patent 14 years

(Cl. D41—1)

FIG.-2

Fig. 1 is a perspective view of a derrick embodying my design, and showing the derrick in a storage position;

Fig. 2 is a perspective view showing the derrick in extended position.

The truck portions shown in broken lines are for convenience of illustration only.

I claim:

The design for a derrick, substantially as shown and described.
